Primary Examiner — Ricky Pham*(74) Attorney, Agent, or Firm* — Hovey Williams LLP(57) **CLAIM**

The ornamental design for a pet treat forming device, as shown and described.

DESCRIPTION

FIG. 1 is a perspective view of a pet treat forming device embodying our design, with a rear hinge element, adjacent hinge mounting structure, forward tabs, and a lower margin of the device being shown in broken lines for illustrative purposes only and forming no part of the claimed design; FIG. 2 is a top plan view of the pet treat forming device depicted in FIG. 1;

FIG. 3 is a front elevation view of the pet treat forming device depicted in FIGS. 1-2, with the lower surface being shown in broken lines for illustrative purposes only and forming no part of the claimed design;

FIG. 4 is a side elevation view of the pet treat forming device depicted in FIGS. 1-3;

FIG. 5 is a rear elevation view of the pet treat forming device depicted in FIGS. 1-4; and,

FIG. 6 is a side elevation view of the pet treat forming device opposite that depicted in FIG. 4.
